CLAIM

The ornamental design for a table, as shown and described.

DESCRIPTION

FIG. 1 is a top, front, left side perspective view according to a first embodiment of my design for a table.

FIG. 2 is a front view of the table shown in FIG. 1.

FIG. 3 is a left side view of the table shown in FIG. 1.

FIG. 4 is a right side view of the table shown in FIG. 1.

FIG. 5 is a rear view of the table shown in FIG. 1.

FIG. 6 is a top view of the table shown in FIG. 1.

FIG. 7 is a bottom view of the table shown in FIG. 1.

FIG. 8 is a top, front, left side perspective view according to a second embodiment of my design for a table.

FIG. 9 is a front view of the table shown in FIG. 8.

FIG. 10 is a left side view of the table shown in FIG. 8.

FIG. 11 is a right side view of the table shown in FIG. 8.

FIG. 12 is a rear view of the table shown in FIG. 8.

FIG. 13 is a top view of the table shown in FIG. 8; and,

FIG. 14 is a bottom view of the table shown in FIG. 8.

The evenly dashed broken lines in FIGS. 7 and 14 represent portions of the table that form no part of the claimed design. The long dash-short dash broken lines in FIGS. 1 and 8 are shading for illustrative purposes.

1 Claim, 14 Drawing Sheets
